UNITED STATES PATENT OFFICE.

GEORGE E. PICKUP, OF NEWARK, OHIO.

DESIGN FOR AN AGRICULTURAL BOILER.

No. 38,991.

Specification for Design.

Patented Jan. 7, 1908.

Application filed October 29, 1907. Serial No. 399,784. Term of patent 7 years.

To all whom it may concern:

Be it known that I, GEORGE E. PICKUP, a citizen of the United States, residing at Newark, county of Licking, and State of Ohio, have invented a new, original, and ornamental Design for Agricultural Boilers, of which the following is a specification, reference being had to the accompanying drawing, forming part thereof.

My invention is shown in the accompany-

ing drawing in which the device is shown by a single figure in perspective illustrating the design of my invention.

I claim:

The ornamental design for an agricultural boiler, substantially as shown.

G. E. PICKUP.
